US00D456412S

(12) **United States Design Patent**
Khovaylo et al.

(10) **Patent No.:** **US D456,412 S**
(45) Date of Patent: **** Apr. 30, 2002**

(54) **OPTICAL SCANNER**

(75) Inventors: **Modest Khovaylo**, Ft Collins; **Jesse M Gerrard**, Loveland, both of CO (US); **Steven Vordenberg**, New York, NY (US); **Philipp Refior**, Brooklyn, NY (US); **Clay Burns**, New York, NY (US)

(73) Assignee: **Hewlett-Packard Company**, Palo Alto, CA (US)

(**) Term: **14 Years**

(21) Appl. No.: **29/140,350**

(22) Filed: **Apr. 17, 2001**

(51) LOC (7) Cl. **14-02**

(52) U.S. Cl. **D14/420**; D14/426

(58) Field of Search D14/420-429, D14/453; D18/36, 37, 39, 54; 250/556; 235/454, 470, 380, 382, 476, 482; 355/64, 65, 75, 81

Primary Examiner—Kay H. Chin

(57) **CLAIM**

The ornamental design for an optical scanner, as shown and described.

DESCRIPTION

FIG. 1 is an isometric view of a scanner;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is An isometric view of a second embodiment of a scanner;

FIG. 9 is a top plan view of the second embodiment;

FIG. 10 is a bottom plan view of the second embodiment;

FIG. 11 is a front elevation view of the second embodiment;

FIG. 12 is a rear elevation view of the second embodiment;

FIG. 13 is a left side elevation view of the second embodiment;

FIG. 14 is a right side elevation view of the second embodiment;

FIG. 15 is an isometric view of a third embodiment of a scanner directed to a scanner right side portion;

FIG. 16 is a top plan view of the third embodiment;

FIG. 17 is a bottom plan view of the third embodiment;

FIG. 18 is a front elevation view of the third embodiment;

FIG. 19 is a rear elevation view of the third embodiment;

FIG. 20 is a left side elevation view of the third embodiment; and,

FIG. 21 is a right side elevation view of the third embodiment.
